US0D1109838S

(12) **United States Design Patent** (10) **Patent No.:** **US D1,109,838 S**
(45) **Date of Patent:** **** Jan. 20, 2026**

(54) **INSECT PEST CONTROL DELIVERY DEVICE**

(71) Applicant: **Shin-Etsu Chemical Co., Ltd.**, Tokyo (JP)

(72) Inventor: **Ryuichi Saguchi**, Joetsu (JP)

(73) Assignee: **SHIN-ETSU CHEMICAL CO., LTD.**, Tokyo (JP)

(**) Term: **15 Years**

(21) Appl. No.: **29/899,132**

(22) Filed: **Aug. 4, 2023**

Related U.S. Application Data

(62) Division of application No. 35/514,352, filed on Nov. 26, 2021 (U.S. filing date under 35 U.S.C. 384), and having an international filing date of Nov. 26, 2021, now Pat. No. Des. 1,000,579.

CLAIM

The ornamental design for an insect pest control delivery device as shown and described.

DESCRIPTION

FIG. 1 is a perspective view of an insect pest control delivery device showing my new design;

FIG. 2 is a front view thereof, a back view being identical thereto;

FIG. 3 is a left side view thereof, a right side view being identical thereto;

FIG. 4 is a top view thereof;

FIG. 5 is a bottom view thereof; and,

FIG. 6 is a reference view showing an example of the insect pest control delivery device that is in use.

The broken lines illustrated in FIG. 6 are for the purpose of illustrating the environment and form no part of the claimed design.

1 Claim, 6 Drawing Sheets
